UNITED STATES PATENT OFFICE.

FRANK W. MERRICK, OF BOSTON, MASSACHUSETTS.

DESIGN FOR A SEAM-WELTING STRIP.

SPECIFICATION forming part of Design No. 27,960, dated December 7, 1897.

Application filed June 28, 1897. Serial No. 642,754. Term of patent 14 years.

To all whom it may concern:

Be it known that I, FRANK W. MERRICK, a citizen of the United States, residing at Boston, in the county of Suffolk and State of Massachusetts, have invented and produced a certain new and original Design for Seam-Welting Strips, of which the following is a specification, reference being had therein to the accompanying drawing.

5 The drawing is a perspective of a portion of a seam-welting strip embodying my design.

10 The characteristic features of my design are the relatively thicker rounded edge 1, having somewhat the effect of a bead or cord, the

main web 2, with its relatively-reduced thickness, having a species of compressed effect, and the knurling or reeding 3 of the surface of the said web.

I claim as my invention—

The design for a seam-welting strip, substantially as shown.

In testimony whereof I affix my signature in presence of two witnesses.

FRANK W. MERRICK.
